(57) **CLAIM**

The ornamental design for an electrode for X-ray tube, as shown and described.

DESCRIPTION

FIG. 1 is a front view of an electrode for X-ray tube of the first embodiment of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a top plan perspective view thereof;

FIG. 8 is a bottom plan perspective view thereof;

FIG. 9 is an enlarged view showing a portion of FIG. 1 defined by line 9-9;

FIG. 10 is an enlarged view showing a portion of FIG. 3 defined by line 10-10;

FIG. 11 is an enlarged view showing a portion of FIG. 4 defined by line 11-11;

FIG. 12 is an enlarged left side view thereof;

FIG. 13 is an enlarged view showing a portion of FIG. 7 defined by line 13-13;

FIG. 14 is an enlarged view showing a portion of FIG. 8 defined by line 14-14;

FIG. 15 is a front view of an electrode for X-ray tube of the second embodiment of the present invention;

FIG. 16 is a rear view thereof;

FIG. 17 is a top plan view thereof;

FIG. 18 is a bottom plan view thereof;

FIG. 19 is a right side view thereof;

FIG. 20 is a left side view thereof;

FIG. 21 is a top plan perspective view thereof;

FIG. 22 is a bottom plan perspective view thereof;

FIG. 23 is an enlarged view showing a portion of FIG. 15 defined by line 23-23;

FIG. 24 is an enlarged view showing a portion of FIG. 17 defined by line 24-24;

(Continued)

FIG. 25 is an enlarged view showing a portion of FIG. 18 defined by line 25-25;

FIG. 26 is an enlarged left side view thereof;

FIG. 27 is an enlarged view showing a portion of FIG. 21 defined by line 27-27; and,

FIG. 28 is an enlarged view showing a portion of FIG. 22 defined by line 28-28.

The features shown in evenly-dashed broken lines depict environmental subject matter only and form no part of the claimed design. The dot-dash broken lines in the drawings represent the bounds of the claimed subject matter, the dot-dash lines, themselves forming no part thereof.
